UNITED STATES PATENT OFFICE.

JOHN W. BODGE, OF CHICAGO, ILLINOIS.

LOCK.

No. 913,942.

Specification of Letters Patent.

Patented March 2, 1909.

Application filed December 21, 1907. Serial No. 407,476.

To all whom it may concern:

Be it known that I, JOHN W. BODGE, a citizen of the United States, residing at Chicago, county of Cook, and State of Illinois, have 5 invented certain new and useful Improvements in Locks, of which the following is a specification.

My invention relates to locks and particularly to that class thereof known as cylinder locks.

More specifically my invention relates to locks of the class generally known as pin-tumbler locks.

Locks of the class mentioned comprise a 15 plug fitting within a casing called the tumbler case, and which operates the bolting mechanism of the lock, by moving the plug in the case, generally by turning it upon its longitudinal axis. The plug is locked against 20 turning by a plurality of split or divided pins arranged in the tumbler case and spring pressed into engagement with corresponding holes in the plug. When the proper key is inserted the several divided pins are moved 25 back until the line of division of each pin is in alinement with the periphery of the plug after which the plug is free to be turned. The pins, or the portions thereof which remain in the plug, are of various lengths and 30 the edge of the key is irregularly notched, so as to cause the ends of the pins to come flush with the periphery of the plug when it is inserted therein. It is possible to make a great number of combinations with a lock of 35 this character by changing the lengths of the several pins and notching the key to correspond; but it should be noted that the great number of combinations possible is due to the unlimited number of changes which can 40 be made in the lengths of the pins, that is, of the portions within the plug.

The object of my invention is to provide a cylinder lock composed of few parts of standard sizes and of such improved construction 45 that an almost unlimited number of different combinations may be had by simply rearranging the tumblers, the sizes of the tumblers or their component parts being unchanged.

50 A further object of my invention is to provide a lock as mentioned, of such construction that a greater number of combinations for a given size of lock may be had.

55 A further object of my invention is to provide a lock as mentioned, of such construc-

tion that a greater number of combinations may be had with a given number of tumblers.

Other objects will appear hereinafter.

With these objects in view, my invention 60 consists generally in the tumbler case and rotary plug in combination with a plurality of two-part tumblers or tumbler pins, the parts thereof within the plug being of two lengths only and interchangeable, a stop to limit the 65 inward movement of the tumblers and a key apertured to permit certain of said tumblers to engage said stop when the same is inserted in the plug.

My invention further consists in a lock 70 comprising a tumbler case and rotary plug in combination with a plurality of two part tumblers, the parts within the plug being of two lengths and interchangeable, and the division line between certain of said tumbler 75 pins being in alinement with the periphery of the plug when in normal position and a key apertured to permit said tumblers to remain in normal position and to move the others into unlocking position.

80 My invention further consists in a lock characterized as mentioned, and having the tumblers arranged in different radial planes.

My invention further consists in various details of construction and arrangements 85 of parts all as will be hereinafter fully described and particularly pointed out in the claims.

My invention will be more readily understood by reference to the accompanying 90 drawings forming a part of this specification and in which,

Figure 1 is a longitudinal section of a lock embodying my invention in its preferred form, Fig. 2 is a similar view illustrating the 95 key inserted in the lock and in position to turn the plug, Fig. 3 is a transverse section through the lock on the line $x-x$ of Fig. 1, Fig. 4 is a similar view on the line $y-y$ of Fig. 2, Fig. 5 is an elevation of the key such 100 as is used with the lock, illustrated in Figs. 1 to 4. Fig. 6 is a transverse section of a modified form of the lock, Fig. 7 is a longitudinal section thereof, on the line $z-z$ of Fig. 6, and Fig. 8 is a detail view of the key, such as is 105 used with the modified form of lock.

Referring to Figs. 1 to 5 of the drawings, 1 indicates the tumbler case which is preferably formed integrally with one side of the lock casing, 2 and having a cylindrical bore, 110

3. Rotatably mounted within the bore, 3 is a cylindrical plug, 4 having a centrally disposed cylindrical keyhole, 5. The inner end of the plug, 4 extends through the lock casing 5 and is somewhat reduced as at 8, forming the annular shoulder, 7 which engages the annular flange, 8, at the bottom or inner end of the bore, 3 to prevent longitudinal movement of the plug inwardly, and an outer shell or casing, 9 is provided which surrounds the tumbler casing, 1 and overhangs the outer end of the plug to prevent outward movement of the latter. The shell or casing, 9 is provided with a keyhole, 10 registering with the keyhole, 5. Upon the inner end of the plug is an eccentric pin, 11 for operating the bolting mechanism of the lock. The tumbler case, 1 and the plug, 4 are provided with a corresponding number of radially disposed tumbler recesses, 12 and 13 respectively in which are arranged the spring pressed tumblers. Each tumbler comprises a spring barrel, 14, arranged within the recess, 12 and the follower, 15 arranged in the recess, 13 of the plug. The follower, 15 may be formed with a spherical end to engage and coöperate with the key, but I prefer to form it cup shaped as shown, and provide a ball, 16 which shall be engaged by the key, the latter offering less resistance to the insertion and withdrawal of the key than the former, and also being subjected to less wear. The spring barrels, 14 are all of the same length, but the followers, 15 are formed of two lengths, 15'—15". Arranged centrally of the keyhole, 5, is a stem, 17. This is cylindrical, and the tumblers, that is the ball, 16, thereof, are pressed into engagement therewith by the springs, 18, arranged behind the spring barrels, 14 or between said barrels and the shell or casing, 9. The followers, 15' are so proportioned that when the balls are in engagement with the stem, 17, their outer ends will be flush with the periphery of the plug and the followers, 15" are somewhat thinner than the followers, 15', hence, at such times the spring barrels, 14 will extend a short distance within the recesses, 13 locking the plug against rotation. The thickness of the followers, 15" is such that when the inner point of the ball, 16 is flush with the wall of the keyhole, 5 the outer end of the follower will be flush with the periphery of the plug. It is obvious therefore, that if a key is inserted which will press the followers, 15" outwardly but which will permit the followers 15' to remain in normal position, the plug, 4 may be turned. To this end I provide the cylindrical key, 20, having the apertures, 21 of sufficient size, and so arranged, as to permit the balls corresponding to the followers, 15' to rest against the stem, 17. When the key is properly inserted the balls corresponding to the followers, 15" will rest against the unapertured portions of the key which will hold the tumblers in position to unlock the plug. If the apertures, 21 are not properly arranged and of the proper number, the plug cannot be turned, for it is obvious that if a follower, 15" is permitted to remain in normal position, or if a follower, 15' is raised out of normal position, the plug cannot turn. To rotatably fix the key within the plug, the bottom of the keyhole is provided with a pin or lug, 22 adapted to engage a notch 23 formed in the end of the key. It is obvious that by rearranging or interchanging the positions of the followers, 15' and 15" or changing the relative number of each, a great number of combinations may be had, and to increase the number of possible combinations I arrange the tumbler recesses in different radial planes. This latter arrangement also admits of a greater number of changes or combinations in a lock of a given size or having a given number of tumblers. In Figs. 1 to 4 I have illustrated rows of parallel tumbler recesses, the rows being arranged in different radial planes, four rows being illustrated at right angles to each other. It will be understood that an infinitely greater number of combinations may be had with the twelve tumblers arranged as shown, than with the twelve similar tumblers arranged in a single row, and also that the lock will occupy a space of substantially one-fourth of the length of one of the latter arrangements. To further multiply the number of combinations possible, the position of the lug or pin, 22 with relation to the tumblers may be varied.

It should be noted that although an almost unlimited number of combinations may be had with the lock above described there is no fitting or cutting of pins to vary their length, nor is any special care or skill necessary in making the key for the lock. Where pins of various lengths are used it is necessary that the serrated edge of the key should nicely conform to the various lengths, however, with the lock above described, it is but necessary to drill the apertures, 21 in the proper positions. In as much as less skill and accuracy is required in making the lock it may be manufactured at a very low cost in comparison with others.

In Figs. 6 and 7 I have illustrated a modified form of lock wherein a flat key is used. This partakes of the general characteristics of the preceding or preferred form, but it is obvious that the central stem, 17 forming a stop for the tumblers must be omitted. It is further obvious that when the stem, 17 is omitted, the tumbler recesses cannot be arranged diametrically opposite from each other. In the modified form the flat keyhole, 5' is angularly shown in Fig. 6, and the tumbler recesses are staggered about the keyhole in such a manner that the opposite wall of the keyhole will constitute a stop to limit the inward movement of the tumblers. The key

24, is provided with a plurality of apertures, 25 corresponding in position to the tumblers having the longer followers, 15' and is equipped with a lug or stop, 26 which limits 5 its movement into the plug. Except for the difference above noted, the modified form of lock is the same in construction and operation as that illustrated in Figs. 1 to 4 and the combinations may be varied in a like manner by changing the relative positions and numbers of the followers, 15' and 15''. To limit the rotary movement of the plug, 4 in order that the tumbler recesses shall properly register when the bolt is in locking position, I 15 provide the coacting lugs, 27 and 28 on the members, 1 and 4 respectively.

Having described my invention what I claim as new and desire to secure by Letters Patent is:

- 20 1. A lock comprising a tumbler case and rotary plug in combination with a plurality of two part tumblers or tumbler pins, the parts thereof within the plug being of two lengths and interchangeable, a stop to limit 25 the inward movement of the tumblers and a key apertured to permit certain of said tumblers to engage said stop when the same is inserted in the plug, substantially as described.
- 30 2. A lock comprising a tumbler case and a rotary plug, in combination with a plurality of tumblers, each said tumbler comprising a spring barrel portion arranged within the tumbler case, a follower portion arranged

within said plug and a ball portion at the 35 inner end, the line of division between certain of said spring barrels and their coacting followers being normally in alinement with the periphery of said plug and the line of division of the remaining tumblers being normally within said plug, substantially as described.

3. A lock comprising a tumbler case and rotary plug in combination with a plurality of two part tumblers, the parts thereof within 45 the plug being of two lengths and interchangeable, a stop to limit the inward movement of the tumblers, a key apertured to permit certain of said tumblers to engage said stop when the same is inserted in the plug 50 and means for rotatably fixing said key within said lock, substantially as described.

4. A lock comprising a tumbler case having a cylindrical bore, in combination with a cylindrical plug fitted within said bore and 55 having a centrally disposed cylindrical keyhole, a plurality of two part tumblers arranged in different radial planes, a stop arranged concentrically within said keyhole and a cylindrical key suitably apertured, 60 substantially as and for the purpose specified.

In testimony whereof I have signed my name to this specification in the presence of two subscribing witnesses.

JOHN W. BODGE.
